CLAIM

The ornamental design for a ball shape remote control holder, substantially as shown in the attached drawings.

DESCRIPTION

FIG. 1 is a perspective view of a ball shape remote control holder, with a lid that opens and closes shown closed, wherein remote control devices which do not form part of the design are shown in phantom as these may be positioned in a pocket of the ball shape remote control holder;

FIG. 2 is a left plan view corresponding to FIG. 1;

FIG. 3 is a right plan view corresponding to FIG. 1;

FIG. 4 is a front plan view corresponding to FIG. 1 (with rear, top and bottom views being the same), wherein a hook-and-loop or VELCRO® fastener does not form part of the design and therefore is shown in phantom;

FIG. 5 is a perspective view of the ball shape remote control holder with the lid that opens and closes shown open to reveal a storage area inside the ball shape remote control holder;

FIG. 6 is a left plan view corresponding to FIG. 5;

FIG. 7 is a right plan view corresponding to FIG. 5;

FIG. 8 is a front plan view corresponding to FIG. 5;

FIG. 9 is a rear plan view corresponding to FIG. 5;

FIG. 10 is a top plan view corresponding to FIG. 5 (with bottom view being the same);

FIG. 11 is a cross sectional view taken through line 11-11 of FIG. 4 showing the top/left perspective view corresponding to FIG. 1 and showing a cylindrical storage area inside the football shape remote control holder;

FIG. 12 is a cross sectional view taken through line 12-12 of FIG. 4 showing the bottom/right perspective view corresponding to FIG. 1 showing the cylindrical storage area inside the football shape remote control holder;

FIG. 13 is a cross sectional view taken through line 13-13 of FIG. 4 showing the top/left perspective view corresponding to FIG. 1 showing an alternative rectangular storage area inside the football shape remote control holder; and,

FIG. 14 is a cross sectional view taken through line 14-14 of FIG. 4 showing the bottom/right perspective view corresponding to FIG. 1 showing the rectangular storage area inside the football shape remote control holder.
